UNITED STATES PATENT OFFICE.

MARTIN KERY, OF ST. CATHERINES, ONTARIO, CANADA.

VEGETABLE CUTTER.

Application filed January 21, 1927. Serial No. 162,549.

This invention relates to certain new and useful improvements in vegetable cutters, and has more particular reference to a device of this kind particularly serviceable for use in slicing cabbages for making cold slaw and for analogous uses.

The primary object of the invention is to provide a vegetable cutter of the above kind which is extremely simple and durable in construction as well as efficient in use.

A further object is to provide a vegetable cutter of the above kind that may be conveniently and effectively operated by foot power.

Still another object is to provide a vegetable cutter of the above kind that may be readily converted for being operated by either hand or foot power, as found most desirable or convenient.

Other objects will become apparent as the nature of the invention is better understood, and the same consists in the novel form, combination and arrangement of parts hereinafter more fully described, shown in the accompanying drawings and claimed.

In the drawings, wherein like reference characters indicate corresponding parts throughout the several views,

Figure 1 is a top plan view of a vegetable cutter constructed in accordance with the present invention;

Figure 2 is a side elevational view thereof, partly in section;

Figure 3 is an enlarged fragmentary side elevational view of the device shown in Figure 2 with parts omitted, and showing the means for permitting hand or foot actuation of the cutter carrying disk;

Figure 4 is an enlarged fragmentary vertical transverse sectional view, taken upon line 4—4 of Figure 2, with parts omitted;

Figure 5 is an enlarged side elevational view of the cutter blade carrying disk; and

Figure 6 is a view partly in vertical section and partly in side elevation, illustrating the cutter carrying plate and the funnel member of the device of Figures 1 to 4 inclusive removed from the table top or platform of the device shown in the latter figures and supported by a barrel for hand operation.

Referring more in detail to the drawings, the embodiment of the invention illustrated includes an elongated platform or table top supported in a horizontal position and at a required elevation by means of corner

supporting legs 6, the upper ends of which are preferably reduced and removably dovetailed into recesses provided in the sides of the table top or platform 5 near the ends of the latter as at 7. The forward end portion of the platform 5 is provided with a relatively large rectangular opening 8 within which is removably fitted a supporting plate or platform section 9. This plate or platform section 9 is properly supported within the opening 8 by providing the upper portions of the wall of the opening 8 with a continuous rabbet so as to define a continuous horizontal shoulder upon which rests the continuous marginal flange 9^a of the plate or platform section 9. As shown more clearly in Figures 1 to 4 inclusive, the platform 5 is provided with a lateral slot at one side thereof intermediate the ends of the opening 8, and the plate or section 9 has a lateral extension 10 fitting and supported in this slot, the purpose of which will presently become apparent.

The plate or platform section 9 is provided with a central longitudinally elongated slot 11 through which projects a vertical cutter-knife carrying disk 12, and this disk 12 is carried by a transverse horizontal shaft journaled upon the underside of the plate or platform section 9 at a point intermediate the ends of the slot 11. In order that the disk 12 may be readily removable for renewal or repair purposes, its supporting shaft is preferably constructed of a pair of sections 13 and 13^a, one of which is removably journaled in a pair of transversely aligned bearings 14 and 14^a at each side of the slot 11, the shaft sections having squared inner ends as at 15 removably fitting in the correspondingly shaped axial opening of the hub 16 of the disk 12. As shown, the shaft sections 13 and 13^a are removably retained in place by providing the outer end portions thereof with annular grooves into which project the set screws 17 carried by the outer bearings 14.

The cutter carrying disk 12 forms part of a conventional cutting unit and is provided with the usual radial equally spaced elongated slots 18 adjacent corresponding longitudinal edges of which are removably secured the radial cutting blades 19 that are secured to one side of the disk 12 as clearly shown in Figure 5. The blades 19 are preferably fastened to the left hand side of the disk 12, and carried by the plate or plat-

form section 9, at the same side of the disk 12, is a tray 20 having its inner end open and adapted to receive and guide the vegetables as they are placed and fed manually 5 toward the adjacent side of the disk 12 for being sliced upon rotation of said disk.

It will be noted that the extension 10 supports the outer bearing 14 of the shaft section 13^a, and the latter shaft section projects outwardly beyond the extension 10 at this side of the machine where it has a spur opinion 21 fixed thereon. The bearings 14 and 14^a of the shaft section 13^a are provided with depending shaft hangers equipped with 15 aligned bearings 22 at their lower ends, and journaled in these aligned bearings 22 is a horizontal transversely positioned crank shaft upon the projecting outer end of which is fixed a relatively large spur gear 23 meshing with and disposed beneath the pinion 21. The outer end of the crank shaft may also be adapted for removable engagement by a hand crank 24 to permit actuation of the cutter carrying disk by hand when found 20 desirable.

The intermediate portion of the crank shaft supported in the bearings 22 is provided with a pair of oppositely directed cranks 25, and removably engaged with 30 these cranks are a pair of depending links 26 which are pivoted at their lower ends to the forward ends of treadles or foot levers 27. Each foot lever is connected to a separate link 26, and is hinged at its rear end 35 to a rear leg connecting brace, as at 28, for vertical swinging movement. As shown clearly in Figure 1, the foot levers or treadles 27 are respectively mounted adjacent opposite longitudinal edges of the 40 platform or table top 5, and the rear end portion of the latter is reduced in width intermediate its end as at 29 to define a relatively wide rear end portion 30, of the platform 5, suitable for use as a seat to be 45 occupied by the operator in a position facing the cutter blade carrying disk 12, so that the operator will be properly seated for convenient actuation of the treadles 27 in causing rotation of the cutter carrying disk. 50 By providing the reduced portion 29, leg clearance is had so that the operator may comfortably straddle this portion of the platform for actuation of the treadles. In order that the cranks 25 may be formed 55 upon a crank shaft mounted at the one side of the cutter knife carrying disk, the pedal 27 at one side of the platform is provided with a lateral offset at its forward end portion as indicated at 31.

60 Rigidly fastened to the underside of the plate or platform section 9 is a tapering funnel member or open bottom hopper 32 that surrounds the slot 11 and the lower portion

of the disk 12. This funnel member 32 is of a length to terminate short of the floor or ground upon which the machine rests, and this enables the positioning of a suitable receptacle 33 beneath the funnel member to receive the cut vegetable as it is sliced by the knives 19 and drops through the slot 70 11 and funnel member 32.

In operation, the operator is seated upon the seat portion 30 of the platform with one foot upon each pedal 27. He then places the vegetables upon the tray 9 and operates the pedals so as to cause continuous rotation of disk 12 at a relatively high speed due to the increase speed gearing formed by the gears 21 and 23. The vegetables are then fed transversely by one hand toward the cutter carrying disk, the same being quickly sliced by the successive engagement of the cutting knives 19 therewith. As the portions are cut from the cabbage or other vegetables, they will fall through the slot 11 and hopper or funnel member 32 into the receptacle 33 placed for their collection.

Should it be found more desirable to actuate the disk 12 by hand and while in a standing position, the plate 9 may be bodily removed from the platform 5 by simply lifting the same after dis-connection of the links 26 from the cranks 25. When the plate or platform section 9 is so lifted the tray 20 and other parts carried thereby will also be removed. It is therefore apparent that the funnel member 32 which is carried by the plate 9 may be placed in the open top of a barrel 33^a as shown in Figure 6 so that the cutting unit thus removed from the platform 5 will be supported by this barrel. Rotation of the cutter may then be readily effected by manipulation of the hand crank 24. Otherwise the general operation is the same as described above in connection with the use of the treadles 27.

From the foregoing description it is believed that the construction and operation as well as the advantages of the present invention will be readily understood and appreciated by those skilled in the art.

Minor changes may be made without departing from the spirit and scope of the invention as claimed.

What I claim as new is:—

A vegetable cutter comprising an elevated platform, said platform including a rigid portion having a removable section, a rotary cutting knife carrying disk journaled upon a transverse horizontal axle on the bottom of said removable section, and means carried by the removable section to facilitate hand operation of said disk when the platform section is removed.

In testimony whereof I affix my signature.
MARTIN KERY.
